UNITED STATES PATENT OFFICE.

ALOYSIUS JOSEPH KUSTERER, OF RICHMOND, VIRGINIA, ASSIGNOR TO CONSOLIDATED PAPER AND BOX MANUFACTURING COMPANY, OF RICHMOND, VIRGINIA, A CORPORATION OF VIRGINIA.

BINDER-BLANK FEED MECHANISM.

Original application filed May 29, 1920, Serial No. 385,361. Divided and this application filed August 10, 1921. Serial No. 491,222.

To all whom it may concern:

Be it known that I, ALOYSIUS J. KUSTERER, a citizen of the United States, residing at Richmond, in the county of Henrico and State of Virginia, have invented certain new and useful Improvements in Binder-Blank Feed Mechanism; and I do hereby declare the following to a full, clear, and exact description of the invention, such as will enable others skilled in the art to which it appertains to make and use the same.

This application is a division of my application for tray making machine, filed May 29th, 1920, Serial No. 385,361. In this application there is described and claimed a mechanism for automatically feeding sheet metal blanks or the like, to be subsequently formed into U-shaped clips and secured to the edges of trays that are formed in the machine described and claimed in said application of which this is a division.

In the drawings in which like reference characters indicate like parts:

Figure 1 is a side elevation of the left hand side of so much of a machine as is necessary to illustrate this improvement;

Figure 2 is a side elevation of the right hand side;

Figure 3 is a plan view;

Figure 4 is an end elevation; partly in section;

Figure 5 is a longitudinal section;

Figure 6 is a plan view of guiding supports;

Figure 7 is a section through one guiding support; on line 7—7 of Fig. 6.

Figure 8 is a perspective of a guide and die, parts being separated;

Figure 9 is a vertical section through a pneumatic feeding device;

Figure 10 is a horizontal section through the feeding arm;

Figures 11 and 12 are details of mechanism for elevating a stack of blanks in a magazine;

Figure 13 illustrates the form of blank handled by the feed mechanism.

The embodiment of my invention herein illustrated and described comprises suitable left and right hand frames 9, the front halves of which are shown.

On that part or end of the framing that is herein designated the front end is a cast-

ing 200. It comprises a table 201 with guide-ways and bearings and two inclined legs 55 202 having base flanges 203 provided with perforations for bolts 204 by which they are rigidly bolted to the upper surfaces of the front portions of members 12 of right side frame 9. The other or left side of the casting 200 is supported by a hollow casting 205 60 designed to function as an air chamber in connection with the mechanism for feeding the tin plate blanks T. Two lateral ears or flanges 206 on the casting 205 are bolted to 65 the left hand edge of said table 201, and a horizontal base flange 207 on said hollow casting is bolted to the upper surface of the front part of member 12 of the left hand side frame 9.

In the top of table 201 is a wide guide groove with under cut sides 209, one of which is formed in a removable gib 210. Near the right hand side of the said wide under-cut guide groove a rectangular channel 211 is sunk, and midway of this channel is an opening 212 to admit the perimeter of a gear wheel. In the guide groove a feed plate 213 is fitted to reciprocate, and on the under side of feed plate 213 there is a rack 214 fitted in the channel 211. The rack 214 projects both forward and rearward of the general front and rear ends of the feed plate 213, and its rack teeth engage the teeth of the gear wheel 215 which project through 70 the said opening 212. On each side of the fore and aft center line of the reciprocating feed plate 213 is bolted an angle plate 216 each having a horizontal and vertical flange. The horizontal flanges of the angle plates 216 are provided with transverse slots 217, and on their under sides with guide ribs 218 of rectangular section which fit in corresponding transverse ways upon the feed plate 213. Bolts 219 pass through the slots 75 into the feed plate and thereby secure the angle plates 216 adjustably to the feed plate so that they may be moved toward and from each other transversely of the machine. The reentrant angles of said angle plates 80 face each other and on the inner faces of the vertical flanges are bolted feed fingers 220, one on each side of the center line of the machine, whereby two tin plate blanks may be simultaneously fed. On the upper edge of 85 each feed finger 220 are two steps forming 90

105

two shoulders, a front shoulder 221 and an intermediate shoulder 222, while on the under side is a single shoulder 223.

Bolted to the table 201 on each side of the longitudinal center line is a guide member 5 and forming die 224 for the tin plate blanks. These members 224 are similar and face each other. Each has a pair of horizontal flanges 225 projecting laterally from its under side, having transverse slots 226 therethrough and transverse ribs 227 on their under sides adapted to fit corresponding grooves in the table 200 and gib 210. Bolts 228 pass through said slots 226 thereby enabling said guide members 224 to be adjusted transversely toward and from each other. The inner faces of the guides 224 lie adjacent the path of movement of the feed fingers 220 for the larger portion of their length and then jut inward to constitute the die block 228 in which the tin plate blank T is formed into a V-shaped blank. Beyond the guide block the guide continues rearward in a grooved guiding extension 229. A mating guide member 230 is spaced from the upper part of the guide 224 between the die block 228 and the front extremity of said guide 224. Each mating guide member has a lateral flange 231 through which bolts 232^a are passed and threaded into the upper end surface of the member 224. In the space between guide 224 and mating guide member 230 the feed finger 220 reciprocates, its end entering and 35 being guided by a groove in the bottom of the matrix of die block 228 and extension guide 229, and the shoulder 221 passing in a groove on the under side of flange 231. The upper surface 232 of guide 224 and 40 mating guide 230 is flat and constitutes the surface on which the tin blanks T are deposited and moved toward the die block 228. At the front end, or deposit end, this surface is considerably wider than the tin plate 45 blanks and is bounded by flanges 233 and 234 parallel for a portion of their extent and then converging as they approach the die block 228, and extending parallel again on each side of the matrix a distance apart 50 equal to the width of the tins T. As the means to be described for depositing the tins on the surface 232 is not adjustable and has always the same amplitude of movement, it will be seen that the width of the 55 surfaces at the point of deposit should be greater than the width of the tins by an extent sufficient to adapt said surface to receive the tins whether the guides 224 be adjusted to their positions of nearest approach or greatest separation, the converging portions 233^a and 234^a of the flanges 233, 234, causing the tins to register with the matrices of the die blocks 228 in any event.

65 The tin plate blanks are held in two stacks

in a magazine or hopper 241 located at the left hand side of the machine frame near the front end, as shown in Figures 1 and 2, two tins being removed simultaneously, one from the top of each stack, and deposited, 70 respectively, on the two tin plate blank guides 224—230, to be ultimately clamped on the two lateral edges of a tray held on a forming block.

The magazine or hopper 241 consists of 75 two similar upright channel guides 242 for the blanks, said channels being open at each end and at their left hand sides. The inner transverse flange 243 of each channel guide is narrower than the outer flange 244. The 80 channel guides are secured together by appropriate connecting bars and the hopper is provided with lugs 245 through which bolts 246 enter the left hand edge of table 201, and a horizontal flange 247 resting on the 85 front end of member 12 of side frame 9 through which passes a bolt 248. Plates 249, adjustably secured to the vertical edges of flanges 244 of the channel guides by means of headed bolts 250 engaging through 90 open ended slots in the plates 249, confine the tin plate blanks against lateral escape, while rendering the contents of the magazine or hopper visible. Other suitable means for confining the tins, such as hinged 95 plates or doors, may be used instead of the slotted plates shown. The spaces between the edges of the flanges 243 and adjustable plates 249 also adapt the hopper to inclose two follower plates 251, integrally connected 100 by a cross tie 252 through said spaces. The cross tie is supported by a projection 253, which has a threaded opening through which a rotary threaded rod 254 engages. In the embodiment illustrated the rod 254 105 has a left hand thread whereby a clockwise rotation imparted thereto at its lower end feeds upward the follower plates 251, and consequently the blanks resting thereon. The upper end of threaded rod 254 is journaled in a cross web or plate 255 bridged across between the upper ends of the flanges 243 of the magazine channels. Its extreme 110 lower end passes through a vertical bearing in a bracket 256 that is bolted to the inner side of the extension 14 on the lower front end of the left hand side member 9. The threaded rod also passes through an opening in the bracket 257 at the lower end 115 of the threaded portion. Secured to the lower end of rod 254 is a hand wheel 258 by means of which the followers may be run down when desired, either to correct the adjustment or for the purpose of refilling the magazine.

120 The tin blanks T previously cut to the desired size and proportions, fit neatly in the channels of the magazine. They may be stacked therein by hand by inserting a few at a time through the sides of the chan-

nels after opening or removing the plates 249, or by manually pushing a full height stack from an independent container that had been previously filled while the machine 5 was in operation. The tops of the magazine channels are about level with the surfaces of the tin guides 224 and the tins are held in the magazine with their long dimensions transverse the lines of feed on the machine, 10 whereby the automatic device, presently to be described, which lifts the blanks from the magazine, and which oscillates through an arc of 90° from the receiving to the depositing positions may deposit the blanks 15 on the guide surfaces 232 in proper position with their long dimensions longitudinal of the machine.

Mechanism is provided to automatically feed the stacks of tin plate blanks upward 20 at such a rate as to maintain the topmost blanks at the same elevation so that two may be picked off at each cycle in the operation of the machine by the automatic device referred to. The mechanism comprises a 25 ratchet wheel 259 secured to threaded shaft 254, said ratchet wheel having a hub, the lower end of which rests on top of the vertical bearing on the bracket. Mounted to oscillate on the shaft 254 and with its under 30 face resting on the upper face of the ratchet wheel 259, is a pawl-carrying plate 260 which is held down on the ratchet wheel by a collar 261 secured to the threaded shaft. To a pin projecting from the lower 35 side of the pawl plate is pivoted a pawl 262, urged by a spring 262^a into contact with the teeth of the ratchet wheel so as to turn it clockwise a partial revolution every time the plate 260 oscillates once. From the upper side of pawl plate 260 projects a pin 263, to which one end of a link 264 is connected. The other end of link 264 is connected to a pin 265 on a block or collar 266 that loosely surrounds the rod-like part 267, 40 that slides in a horizontal bearing 268 on the said bracket 256 and is part of a cam fork 269. The collar 266 presses against a hooked pin 266^a, secured to rod 267, in one direction, and is urged in that direction by 45 a spring 273. The pawl 262 has a short handle or tail piece 262^b by which it may be manually held out of engagement with the ratchet teeth in order to permit the screw rod 254 to be rotated counter-clockwise by 50 the handle 258 in order to lower the followers 251. A spring detent 259^a rests against the ratchet wheel to prevent a return movement of the screw 254 when the pawl retracts to engage another ratchet tooth in 55 a manner well known in connection with ratchet and pawl mechanism. The cam fork 269 carries a roller stud 270 that engages a cam projection 271 on the perimeter of a cam 312 secured to shaft 16^t, the forked 60 end of the cam fork passing astride a flanged

hub on said cam 312. The compression spring 273 surrounding the rod 267 and bearing at one end against the slidable collar 266, bears at the other end against a shoulder formed at the junction of the rod 267 with the cam forked portion 269. Thus the collar 266 is pushed forward once at each revolution of the cam 262, or once in each complete cycle of the machine by the yieldable spring 273; and if any considerable resistance occurs between the collar and the magazine follower the spring 273 will yield and no damage be done. The hooked stop pin 266^a has one end of a coiled tension spring 274 attached to it, the opposite end 75 of said spring being attached to a stud or bracket 275 secured to the left hand side frame 9. Spring 274 holds the roller stud 270 on the cam fork 269 against the perimeter of the cam 312. The end of the rod 267 carries two nuts 276 which stop the inward movement of the cam under the pull of spring 274 against the bearing 268, and may serve as an adjusting means to determine the extent of reciprocation of said cam 80 form and adjust the ratchet feed. The throw of cam 271 is so timed that the upward movement of the stacks of tins takes place when the oscillatory conveyer or feed arm is in its lowest position over the magazine and normally in contact with the topmost tins. If an over-feed has occurred the spring 273 will yield and prevent injury while at the same time the topmost tins will be kept snugly against the pneumatic face of 90 the conveyer arm of the automatic feed device to be described.

The tins are removed from the top of the magazine in pairs and deposited in pairs on the wide portions of the surfaces 232 of guides 224 by an oscillatory hollow pneumatic conveying device 277, which is an angular body, seen in elevation, having a horizontal arm 278 and a vertical hollow shaft 279, the latter being fitted, air tight, in the hollow casting or air chamber 205, before mentioned, so as to oscillate therein. The lower end of the hollow shaft 279 has a reduced solid end 280 projecting through the lower end of the casting 105, and to this end 105 portion 280 the mechanism for imparting the necessary movements to the arm 278 is connected. Extending transversely of the hollow arm 278 on its under side near its end are two parallel, flat, oblong, slightly 110 projecting faces covered, preferably, with flat plates 281 of brass or other non-magnetic material, holes piercing these plates and extending through the wall of the hollow arm 278. The plates are of a size and outline and are approximately spaced to fit suitably upon the uppermost tins in the magazine stacks. In the wall of the hollow shaft 279 is a lateral air port 282, which 115 opens into a chamber 283 within the cast- 120

ing 205. A hollow branch of casting 205 extends transversely toward the center line of the machine and has a valve chamber 284, inclosing a valve seat 285, below which is a 5 chamber communicating with a nozzle 284^a adapted to be connected to a conduit containing an exhaust fan or leading to any suitable means for withdrawing air. A valve 286 is arranged to open and close communication between the chamber and the 10 exhaust connection. A valve stem 287, threaded to the valve 286 (which is adjustably held by a lock nut thereon) is guided in the lower wall of the valve chamber, and 15 a continuation 288 of said stem extends through a removable cap 289 closing an opening on the upper side of the chamber 284. The orifice covered by the cap 289 is large enough to permit removal of the valve 20 286 therethrough. The lower end of valve stem 287 is threaded and passes through a hole in the offset end 291 of a cam fork 292, and is not adjustable here, simply locked, and secured thereto by threaded nuts 287^a. 25 The valve is adjustably threaded and locked on its stem. The cam fork 292 carries a roller stud 293, which bears upon the periphery of a quick throw cam 294 secured on the hub of the adjacent cam 328 which is 30 secured on shaft 16^T, and the forked end slides astride an annularly grooved part of the hub of said cam 328. The cam 294 lifts the valve so that air may be withdrawn from the hollow conveyor arm at that portion of 35 the cycle when the plates are to be lifted from the magazine and transferred to the guides 224 and releases the valve so that the weight of the valve, its stem and the cam fork 292 will seat it again when the tins 40 are deposited on the said guides. When the valve 286 is open an air exhaust means (not shown) causes sufficient reduction of pressure within the conveyor arm to hold the tins against the faces of the plates 281, and 45 when the connection with the air exhaust means is cut off by closure of the valve 286, there is sufficient seepage of air around the stem passage in the cap 289 to soon equalize 50 the pressure again while the conveyor is at rest in position to release the tins. Obviously a vent and vent valve may be controlled by the said valve stem if desired.

In conveying the tins from the magazine to the guides, a down and up movement is 55 imparted to the conveyor 277, in order to pick the tins from the magazine, and a down and up movement is imparted to said conveyor after the arm 278 has swung 90° from the magazine to the point of deposit. 60 Mechanism to be now described is provided for imparting both the vertical and oscillatory movements to said conveyor.

Upon the reduced end 280 of the vertical shaft 279 is splined a miter gear wheel 295, as shown in Figure 4, so that the shaft 280

and miter gear wheel 295 rotate together but the shaft may move vertically through the hub of said miter gear. The upper end of the hub of the gear 295 bears against the lower end of the hollow chamber 205 where the shaft extension 280 emerges, and a bracket bearing 296 bolted to the air chamber casting 205 supports said gear from beneath. The said bracket 296 (Figures 1 and 4) also has two horizontal alined bearings in 70 which a shaft 297 is journaled, said shaft carrying a miter gear 298 meshing with the miter gear 295. The hub of gear 298 bears against one face of one of said horizontal alined bearings, and secured on said shaft on 75 the other side of the same bearing is a crank arm 299 having a hub lying against said bearing so that the shaft is secured against any lengthwise movement. The outer end of crank arm 299 is slotted at 300 (Figures 1 and 2). A stud 301 is adjustably mounted in the slot. On the stud is pivoted or swiveled a connector 302 having a hole at right angles to the stud 301, through which passes the threaded end of a cam fork 303 secured 80 on each side of the connector by adjustable nuts 304. The cam fork 303 carries a roller stud 305 which engages a cam groove in the left hand face of a cam 306 secured on shaft 16^T, astride the hub of which cam 306 the 85 arms of the cam fork reciprocate. The groove in the cam is so designed as to cause a dwell or period of rest at the end of each outward or inward stroke. The amplitude of movement of crank arm 299 may be varied by adjusting the stud 301 in the slot 300, and the locus, or the beginning and ending points of the arc of oscillation may be changed by adjusting the nuts 304. The 90 amplitude of throw of the cam is such that, with the transmission used, the arm 278 may oscillate through an arc of 90°, included between lines longitudinal and transverse of the machine intersecting at the axis of oscillation.

Stop brackets 278^a carrying adjustable stop screws 278^b may be provided if desired one at each end of arc of movement of arm 278 to prevent any over movement of arm 278 toward depositing or picking up position in case of looseness of operating parts.

In order to impart the necessary up and down movement to the pneumatic feed device 277, the following described mechanism is provided:

Between two collars 307, secured to the lower end of the extension 280 of the vertical hollow shaft 279 (Figures 1 and 4), is a collar 308 on the branched ends 309 of a cam fork 310 which carries a roller stud 311 engaging a cam groove in the cam 312 secured to shaft 16^T. The groove in cam 312 is designed to impart two reciprocations to the cam fork 310 at each revolution and to produce a rest or dwell beneath each upward 120

- and downward movement. The said movements and dwells are timed with respect to the oscillations of the arm 278 so that the arm will drop to seize two plates, rest on them long enough to assure seizure, rise, swing to the point of deposit, drop, rest long enough to assure release after valve 286 is closed, again rise and swing back to initial position over the magazine.
- 10 In order that the flat tin plate blanks T deposited on the guides 224 by the arm 278 may be fed to the die block 228, and the V-shaped blanks stamped by the die plates 329 may be fed to the forming mechanism, the feed plate 213 carrying the feed fingers 220 must be reciprocated once during every cycle of the machine, so that the shoulder 221 of each feed finger, which shoulder projects above the surface 232 of the guides 224, may 15 engage the ends of the tin plate blanks T and push them over the matrices 236 in die blocks 228; and the tips of the fingers 220 on the next forward movement will engage the V-shaped blanks in the matrix grooves 236 and push them onward through the grooves 238 to the clamping jaws, (described in said prior application), which clamp the V-shaped fins onto the edges of the tray formed on the forming block. To reciprocate the feed plate 213 the gear wheel 215, before mentioned, must be oscillated or alternately rotated in opposite directions. The gear wheel 215 is secured to a shaft 330 journaled in hangers 331 depending from the table 201. Secured to said shaft 330 on the right hand end, outside of the right hand hanger 331, is a pinion 332. On the right hand hanger is a slide bearing 333 having a groove to receive and guide rack 334, said groove being closed by a face plate 335. The rack 334 has offset parallel end members 336 having aligned perforations through which passes a rod 337 having nuts 338 threaded to its upper end outside the upper offset 336 on the rack. Above the lower offset a collar 339 is adjustably secured on the rod, and a coiled expansion spring 339^a surrounds said rod, having one end bearing on collar 339 and the other end bearing upon the upper offset 336, whereby an upward thrust is applied yielding to the rack 334. The lower end of rod 337 is threaded into the upper end of a cam fork 340, which carries a roller stud 341, engaging a cam groove in the right hand face of cam 342 secured on shaft 16^a, and the forked arms of said cam fork are guided astride the hub of said cam 342. The groove of cam 342 is so designed as to give a dwell to the feed plate 213 at the limit of its movement to the stacking position and a quick reciprocation. Should the tins choke in the path of the feed finger the spring 339^a will yield and no damage can result. The inclined shoulder 222 on the upper edge of each feed finger and the inclined shoulder 223 on the lower edge provide ample clearance to avoid frictional wear on cover plate 239 and engagement of the end of the finger with the die block 228 when the finger enters the channel below the V-shaped matrix 70 groove.
- Two stacks of sheet metal blanks T having been placed in the magazine 241 provided for them near the front of the machine, and the followers 251 adjusted so as to bring the 75 topmost blanks to the top of the magazine, the machine is ready for operation. At the commencement of a cycle two tins are resting in the matrix grooves, the feed fingers 220 are at their front or starting position, 80 the pneumatic conveyer arm 278 is over the magazine 241. As the drive shaft rotates, at the proper instant with relation to the movements of associated mechanism, the pneumatic conveyor arm 278 drops to bring 85 the perforated plates 281 onto the two top blanks T in the magazine, the valve 286 has opened and the air pressure has been reduced in the arm 278, arm 278 is then lifted, swung 90°, dropped so as to place the blanks T longitudinally on the surfaces 232 of the guides 224, and the valve 286 closed, releasing the blanks T on the guides, in position for the shoulder 221 of the feed fingers 220 to engage them and advance them to the bending 95 dies.
- What I claim and desire to secure by Letters Patent is:
1. In a tray forming mechanism, the combination of a guide for blanks, a magazine adapted to hold a stack of oblong blanks transversely of the guideway, an oscillating arm adapted to transfer blanks from the magazine to the guideway, said arm moving through an angle of ninety degrees whereby 100 to deposit the blanks lengthwise of the guideway and a rigid abutment at the top of the stack for preventing the stack from raising above a certain height.
  2. In a tray forming mechanism, the combination of a guideway for blanks, a magazine adapted to hold a stack of oblong blanks transversely of the guideway, an oscillating arm adapted to transfer blanks from the magazine to the guideway, and adjustable 105 stop devices arranged to stop the arm at each extremity of its oscillation.
  3. The combination of a magazine for blanks, a guideway for receiving said blanks, an arm adapted to oscillate between the magazine and the guideway to transfer blanks from the former to the latter, said guideway having converging confining walls for the blanks and means for adjusting the guideway transversely, the arrangement of the 110 guideway and oscillating arm being such that the blanks will be deposited on the wider portion of the guideway.
  4. In a tray forming machine, a guideway 115 for blanks having a central longitudinal 120
- 60 65 70 75 80 85 90 95 100 105 110 115 120 125 130

- space, a feed finger reciprocating in said space, said feed finger having a shoulder extending above the surface of the guideway and adapted to engage the edge of a blank.
5. In a tray forming mechanism, a feed mechanism for metal blanks comprising a reciprocable rack, a gearing for reciprocating said rack, a reciprocating rack for oscillating said gearing, said last mentioned rack having offset members at its opposite ends, a reciprocating rod over which the ends of said rack are sleeved, a spring surrounding said rod and tending to press said rack toward the end thereof and adapted to yield in the event of abnormal obstruction, and means for reciprocating said rod.
6. In a tray forming mechanism, a magazine for holding a stack of blanks, a follower for feeding the stack upwards, a screw for advancing the follower, mechanism for rotating the screw step by step, a yielding device actuating the step by step mechanism whereby the latter will cease to act in case of abnormal obstruction and a rigid abutment at the top of the stack for preventing the stack from raising above a certain height.
7. In a tray forming mechanism, a magazine for holding a stack of blanks, a pneumatic feed device adapted to be brought in contact with the top of the stack to remove the blanks one by one from the magazine, a follower adapted to feed the blanks upward, a screw for operating the follower, a device for intermittently rotating the screw, a yielding means for actuating said intermittently acting device, a means for actuating the feed device, a means for actuating said yielding means so timed that the yielding means will be actuated when the feed device rests on top of the stack and a rigid abutment at the top of the stack for preventing the stack from raising above a certain height.
45. 8. In a tray forming mechanism, a magazine for holding a stack of blanks, a pneumatic conveying device adapted to descend on the topmost blank and then remove it from the stack, a follower for elevating the stack, an intermittently acting device for elevating the follower, a sliding means on the intermittently acting device adapted to yield and prevent feeding in the event of abnormal obstruction, the means for actuating the conveying device and the follower elevating device being so timed that the follower elevating device operates when the conveying device is in position to remove a blank from the stack.
60. 9. In a tray forming mechanism, a magazine for holding a stack of blanks, a follower adapted to feed the blanks upward, a screw for operating the follower, a ratchet on the screw, an oscillating pawl carrier and pawl, a reciprocating bar adapted to oscillate said pawl carrier, a slide bearing for said bar, a cam for moving said bar in one direction, and a spring for retracting it, and an adjustable stop on the reciprocating bar arranged to engage the slide bearing, and limit the retracting movement of the reciprocating bar, whereby the amplitude of the oscillation of the pawl carrier may be varied.
10. In a tray forming mechanism, a magazine for holding a stack of blanks, and means for feeding the stack upward, a hollow shaft having a laterally extending hollow arm having a perforated contact surface adapted to hold a blank, regulatable means for reducing the pressure within said arm below atmospheric comprising a valve, means to oscillate said arm, from a position where the contact surface is over the magazine to a position of deposit, means formed to cause the arm to descend at one end of its oscillation to bring the contact surface against a blank, and then rise, and to lower the arm and raise it at the other end of its oscillation, and mechanism timed so as to open the valve at the time of contact with a blank and retain it open until the arm has descended at the end of its oscillation and then to close the valve before the arm again rises.
11. In a tray forming mechanism, a magazine, an air chamber having a nozzle adapted to be connected with an air exhaust device, a valve for controlling the passage of air from the chamber, a hollow shaft rotatable and vertically slidable with respect to said chamber, said hollow shaft having an air port communicating at all times with said chamber, a pneumatic conveyor arm projecting from said shaft adapted to remove blanks from said magazine, means to oscillate said shaft and means to reciprocate said shaft in proper time to lift, remove and deposit a blank, and means timed to open said valve when the arm is in position to lift, convey and deposit a blank, and to close as soon as the arm has reached the depositing position.
12. In a tray forming mechanism, a pneumatic feed mechanism, comprising an air chamber having a port adapted to be connected with an air exhausting device, a valve chamber and a horizontal partition containing a valve seat adjacent the port within the chamber, a valve stem passing through the walls of the chamber above and below said partition, a valve adjustably threaded to the valve stem, a rod depending from the lower end of the valve stem and a cam disposed to push the rod upward but permit it to descend by gravity only.
- In testimony whereof I affix my signature.

ALOYSIUS JOSEPH KUSTERER.
